PHONOGRAPH RECORD CHANGING
MECHANISMPaul U. Lannerd, Elyria, Ohio, assignor to The
General Industries Company, Elyria, Ohio, a
corporation of Ohio

Application June 25, 1934, Serial No. 732,248

23 Claims. (Cl. 274—10)

This invention relates to phonograph mechanisms and particularly to phonograph mechanisms whereby a plurality of records of the disc type may be played one after the other automatically.

Heretofore, phonograph mechanisms have been proposed whereby a pile or tier of disc type records on the phonograph turntable may be played one after the other. After one record has been 10 played, the reproducing head of the phonograph is returned to the starting point and the played record is removed from the pile, and so on until all of the records have been played.

Such prior phonographs however have been 15 capable of automatically playing and changing records of one size or diameter only, for example ten inch records; and when, say, twelve inch records are to be played, the mechanism must be manually controlled.

It is therefore an object of the present invention to provide an improved phonograph mechanism whereby a plurality or pile of disc-type records may all be played one after the other automatically and having means adapting the 25 mechanism to a plurality of sizes or diameters of records.

Another object is to provide a phonograph mechanism of the type referred to particularly adaptable to portable types of phonographs.

Another object is to provide an improved phonograph mechanism of the type adapted to play 30 successively and automatically a pile or tier of disc records.

Another object is to provide, in a phonograph 35 mechanism adapted to drive the turntable at a plurality of speeds to adapt it to records which have been produced at different speeds, and comprising automatic means driven from the phonograph motor to change the records automatically, improved means for operating the record changing 40 mechanism at the same speed irrespective of the adjustably changed speed of the turntable.

Another object is to provide, in an automatic 45 record changing phonograph mechanism, improved means for feeding the reproducing needle onto the successive records at the beginning thereof.

Another object is to provide an automatic 50 phonograph mechanism of the class referred to provided with means whereby a single record may be repeatedly played; or a pile of records may be automatically played one after the other; or a single record may be played once only and thereafter the mechanism automatically stopped; and improved means whereby during the playing of

any one record, the playing thereof may be manually stopped.

Other objects will be apparent to those skilled in the art to which my invention appertains.

My invention is fully disclosed in the following 5 description taken in connection with the accompanying drawings, in which:

Fig. 1 is a top plan view of a portable phonograph embodying my invention;

Fig. 2 is a front elevational view of the phonograph of Fig. 1; 10

Fig. 3 is a top plan view of mechanism of the phonograph of Fig. 1, drawn to a larger scale, and with a phonograph disc or discs of Fig. 1 omitted, and illustrating the disposition of certain parts thereof when the phonograph is to play 15 twelve inch records;

Fig. 4 is a view similar to Fig. 3 with some of the parts in different operative positions;

Fig. 5 is a fragmentary view similar to a part 20 of Fig. 3 with parts in different operative positions;

Fig. 6 is a fragmentary view to an enlarged scale taken from the plane 6—6 of Fig. 1, illustrating part of a record changing mechanism; 25

Fig. 7 is a view similar to Fig. 6 illustrating parts thereof in different positions which they assume in the operation of changing a record.

Fig. 8 is a fragmentary sectional view to an enlarged scale taken from the plane 8 of Fig. 3, 30 further illustrating the record changing mechanism;

Fig. 9 is a fragmentary view similar to a part of Fig. 3 illustrating the disposition of certain 35 adjustably movable record changing parts when the mechanism is to play ten inch records;

Fig. 10 is a sectional view to an enlarged scale taken from the plane 10—10 of Fig. 4, showing some parts omitted from that figure for clearness; 40

Fig. 11 is a sectional view taken from the plane 11—11 of Fig. 3;

Fig. 12 is a sectional view taken from the plane 12—12 of Fig. 4 with parts omitted for clearness; 45

Fig. 13 is a sectional view taken from the plane 13—13 of Fig. 3 showing parts omitted from that figure for clearness;

Fig. 14 is a plan view of a tone arm which I may employ with an adjustable stop device thereon; 50

Fig. 15 is a view similar to Fig. 14 with parts thereof in different positions;

Fig. 16 is a front elevational view of the tone arm and a stop device which I may employ, the 55

stop device appearing as if viewed from the left end portion of Fig. 15;

Fig. 17 is a view similar to Fig. 16 with parts thereof in different positions;

Fig. 18 is a view partly diagrammatic illustrating a motor control system which I may employ;

Fig. 19 is a cross-sectional view taken approximately from the plane 19-19 of Fig. 3, illustrating a motor drive for the phonograph turntable.

Fig. 20 is a fragmentary sectional view taken from the plane 20-20 of Fig. 13;

Fig. 21 is a fragmentary sectional view taken from the plane 21 of Fig. 14;

Fig. 22 is a fragmentary sectional view taken from the plane 22 of Fig. 18;

Fig. 23 is a fragmentary view similar to a part of Fig. 19 showing parts thereof in different operative positions;

Fig. 24 is a plan view taken from the plane 24 of Fig. 23.

Referring to the drawings, Figs. 1 and 2, I have shown in portable form a phonograph reproducing mechanism embodying my invention of the type adapted to energize a remotely disposed amplifier or loud speaker, the mechanism being housed in a carrier proper 1 and a cover 2 therefor, the carrier having a carrier handle 3, the cover connected thereto by hinges 4-4, and the carrier and cover being shown in solid lines in the open or operative position and in Fig. 2 the cover being shown in the closed position in broken lines.

35 A motor 5 in the carrier is drivingly connected to a turntable 6 through a two-speed drive shown separately in Fig. 19 and at either speed, the running speed may be adjustably varied for the usual purposes.

40 The turntable shaft 7 projects upwardly through the turntable 6 far enough to center on the turntable a plurality or pile of record discs, to be played one after the other. A tone arm 9 has a reproducing head 10 provided with a 45 needle 11 and is mounted to oscillate laterally and vertically upon a base 12 supported upon a panel 13 mounted in the carrier 1. At 14 generally is a mechanism to be described for lifting the tone arm from the record at the completion 50 of playing thereof and returning it to the starting point of the next record of the pile. During this operation, a mechanism indicated generally at 15 removes from the pile the top record which has been played and discharges it over into the cover 2 as a receptacle therefor in a manner to be described.

55 In the cover 2 has a false bottom 16 hingingly connected to the inside of the cover at 17 and at the opposite side of the cover being hingingly connected as at 18 to a prop 19 constantly under the impulsion of a spring 20. When the cover 2 is in the open position illustrated in Figs. 1 and 2, the false bottom 16 may be operatively raised to allow the prop 19 to move counter-clockwise to the position indicated thereby elevating the false bottom to a relatively steeply inclined position, upon which discs 8 discharged from the turntable 6 may be slidingly deposited. When it is desired to close the carrier by rotating the cover to the broken-line position Fig. 2, the prop 19 may be operatively moved in under the false bottom 16 and the discs 8 may all be placed on the turntable shaft 7 and then the cover rotated to the closed position. Thereupon the 70 false bottom 16 at the end opposite the hinge 75

17 will fall down upon the discs 8 and the prop 19, under the impulsion of the spring 20, will move upwardly into engagement with the inner side of the cover 2 and serve as a retaining device to prevent the discs 8 from coming off 5 from the shaft 7, causing them to be retained on the turntable 6 to prevent damage thereto which might occur if they were free to rattle around loosely within the carrier.

The reproducer head 10 is preferably of the 10 electro-dynamic type generating current impulses and wires 21 (Fig. 13) leading from the head 10 through the tone arm 9 and downwardly through the base 12 are led out of the carrier 1 as shown in Fig. 1 and may be plugged in in 15 a well known manner to the loud speaker or amplifier employed in connection with the apparatus.

A double cord 22 having the usual two-prong plug 23 thereon may lead into the carrier 1 and 20 under the panel 13 to the motor 5 under the control of a two-way switch 24 on the panel 13 as shown in Fig. 1 and as shown diagrammatically in Fig. 18; and as also shown in Fig. 18, the motor 5 is under the control of a mechanism-25 operated switch indicated generally at 25 and to be described.

The motor 5 may be of any usual or known construction mounted in a housing indicated generally at 26, Fig. 2, and a part of which is 30 illustrated in Fig. 19. The drive for the turntable 6 is illustrated in Fig. 19 and will now be described.

A worm 27 driven by the motor in a manner not shown but well known in the art meshes 35 with a worm wheel 28 running idle on the shaft 7 and meshes with a worm wheel 29 keyed to a countershaft 30. A spur gear 31 keyed on the countershaft 30 meshes with a spur gear 32 running idly on the shaft 7. A clutch device 33 40 keyed or splined on the shaft 7 is reciprocable thereon by oscillation of a shaft 34 to engage clutch teeth 35 and 36 alternatively on the gears 32 and 28 respectively. On movement of the clutch device 33 upwardly as viewed in Fig. 19, 45 the motor will drive the turntable 6 through the worm 27, gears 29, 31, 32, clutch device 33-38, and shaft 7, the turntable 6 having for this purpose a hub 37 resting upon a collar 38 on the shaft, the speed of this driving connection 50 being a relatively low speed. Upon shifting the clutch device 33 downwardly, the drive will be from the worm 27 through the gear 28, clutch device 33, teeth 36 and to the shaft 7, and this drive will be at a relatively low speed. These 55 speeds as well known in the art and commercially may be at the ratio of 33 to 78 for well known reasons.

The gear 32 has an upwardly extending hub 39 upon which is secured an upwardly open 60 generally cup-form cam device 40 (see also Fig. 3), the cup skirt of which is approximately semi-cylindrical, the cam device 40 at its closed cup bottom portion being telescoped over the hub 39 and secured thereto by a screw or screws 65 such as 41. The upper edge 42 of the cam device is normally covered and concealed by portions of the turntable 6.

As will be apparent from the mechanism of Fig. 19, the cam device 40 is always driven at 70 the same speed regardless of which of the two speeds of the drive are propelling the turntable 6, the device 40 being driven directly from the worm 27 through the gear 29 and gears 31 and 32. The cam device 40 as will presently be 75

described operates the mechanism to return the tone arm and discharge the played record; and by driving it always at a constant speed, it will operate said mechanism more reliably and efficiently than if it rotated at different speeds at different times.

The shaft 34 has a laterally extending arm 43 engaged by a horizontally oscillatable arm 44 connected to a horizontally oscillatable speed adjusting arm 45 by a vertical stub shaft 46, the arm 45 extending outwardly under the adjacent edge of the turntable 6 to render it accessible.

The support for the turntable 6 is illustrated and described more completely in the copending 15 patent application of William A. Schmittgen, Serial No. 513,361, filed February 4, 1931, and the two-speed drive and clutch device 33 are more fully illustrated and described in the copending application of Fritz Van der Woude, Serial No. 20 595,012, filed February 25, 1932, and reference may be had thereto for a complete description of these parts if desired. They constitute no essential part of the present invention except in so far as they predetermine two selective speeds for the turntable and a constant speed for the cam device 40.

The mechanism for playing a plurality of records one after the other will now be described in connection with its mode of operation.

30 It will be assumed that a pile of records 8-8 of the twelve inch diameter size are placed on the turntable as shown in Figs. 1 and 2, this being one of the two preferred sizes to play which the apparatus is provided. The motor 5 is started by throwing the switch 24 to the "A" position, Figs. 1 and 3 and 18, which closes the motor circuit from the wires 22 through the switch 24. The speed of the motor is adjusted by moving the arm 45, Figs. 1, 3 and 19, to set 35 the motor speed to the predetermined speed of the records, the extreme speed positions of the lever 45 being determined by suitable stops 47 and 48 on the panel 13, Fig. 3, and the running or tone speed of the turntable may be adjusted 40 by a lever 49 toward "F" for faster or "S" for slower by mechanism not shown but well known in the art. One such mechanism is shown in the patent of F. Van der Woude No. 1,936,924, issued November 28, 1933.

50 The head 10 of the tone arm 9 may be grasped by the operator and the tone arm may be rocked upwardly and then swung laterally on the base 12 and then lowered to place the needle 11 in the record groove at the beginning of the record. 55 The base construction supporting the tone arm 9 for these movements may be of any suitable construction not essential to the present invention. One form is shown in Fig. 13 and comprises an inverted cup-form sheet metal base proper 60 70 resting upon the panel 13 secured thereto by a plurality of screws 71, the base having an inner partition 72, and perforations at 73 in the bottom of the cups 10 and 74 spaced therefrom in the partition 72, guide oscillations of a stem 75 projected through the perforations; and a nut 76 on the lower end of the stem prevents the stem from moving outwardly from the perforations and a forked head 77 on the upper end of the stem supports the tone arm.

70 In the preferred construction, the tone arm is of inverted channel section as shown in Fig. 20 and the head 77 has upwardly projecting arms 78-78. Pivot-pointed screws 79-79 are threaded through the flanges of the channel and are seated at their pivot points in suitable recesses

in the arms 78-78. The stem 75 is hollow and the wires 21 above referred to are suitably conducted downwardly therethrough as shown in Figs. 13 and 20.

The head 77 has a bracket 80 extending therefrom, Fig. 13, supporting a pivot pin 81 to be referred to.

As will now be apparent, the tone arm may swing laterally by rotating the head 77 and stem 75 and may swing vertically on the pivot screws 10 15 79-79. The movements of the tone arm 9 may be counter-balanced by a weight 82 rearwardly of the pivot bearings 79-79.

The needle now follows the groove of the record and the record is played, the needle ultimately 15 reaching the inner termination of the record generally at the central portion of the disc. It will be presumed that the disc is of the type having a spiral terminal groove, and when the needle reaches the spiral thereof, it will be given an 20 accelerated quick movement inwardly radially and thereby set into operation the following mechanism.

As shown in Fig. 3, a lever 51 pivotally mounted upon the panel 13 at 52 has the lower end 53 pointed. A triangular shaped arm 54 extends laterally from the lever 51 and a tension spring 55 hooked at one end into the arm 54 and at the other end hooked into an eye 56 on the panel exerts resilient force tending to rotate the lever 51 25 counter-clockwise as viewed in Fig. 3. Rotation is prevented by a dog 57 on the lever 51 engaged with a notch 58 on a lever 59 extending transversely of the lever 51 and pivotally connected at 60 to the panel 13. The lever 59 is resiliently 30 constrained in the counter-clockwise direction by a tension spring 61 hooked at one end into the lever and at the other end hooked into an eye 62 35 on the panel.

A cam arm 63 is pivoted to the panel as at 64 40 at one end and at its opposite end extends under the lever 59 and has a V-notch in the end providing a pair of oppositely inclined cam surfaces 65 and 66. A cam follower pin 67 on the lever 59 is normally disposed in the notch between the 45 cam faces 65 and 66. The cam arm 63 has a post 68 thereon extending upwardly therefrom.

Reference may be had to these parts also in Figs. 5, 10, 11 and 12.

As shown in Fig. 3, a finger 84 movable with 50 the tone arm 9 will move toward the post 68 and ultimately engage the same, but before describing the action thereof, the finger 84 will be more fully described in connection with Figs. 11, 12 and 13. A three-fingered element 85 is pivotally 55 supported on the pin 81 and comprises three fingers extending forwardly from the pivot, an upper finger 86, an intermediate finger 87 and the lowermost finger being the finger 84. A tension spring 88 is connected at its upper end to the element 85 and at its lower end to the bracket 80 forwardly of the pivot 81 and thus resiliently 60 constrains the element 85 to rock counter-clockwise around the pivot 81 as viewed in Fig. 13.

A bracket 89 is secured transversely in the tone 65 arm 9 (see Fig. 14) by screws 90 and flanges 91 on the bracket 89. The bracket 89 and fingers 86 and 87 are disposed so that when the tone arm 9 is lifted, the bracket 89 will engage the upper finger 86 to prevent excessive counter-clockwise oscillation of the element 85, and so that when the finger 84 is elevated in a manner to be described, the finger 87 will engage the under side of the bracket 89 and lift the tone arm 9.

Upon the lower end of the finger 84 on the under side thereof is a foot 92 and a roller 93. During playing of the record in the normal position of the tone arm, the foot 92 rests upon the upper side of the lever 59 as shown in Figs. 11 and 13. As above mentioned, in connection with Fig. 3, the finger 84 thus moves laterally bodily with the tone arm 9 and when the reproducing needle reaches the spiral terminal groove 10 of the record and the finger 84 is given an accelerated final movement, it engages the post 68 and moves the cam arm 63 with it, causing the cam face 66 to slide upon the pin 67 thereby moving the lever 59 about the pivot pin 60 disengaging the notch 58 from the dog 57 against the tension of the spring 61.

Thereupon, the spring 55 rocks the lever 51, moving the pointed end 53 to the broken line position, disposing the point thereof in the path 20 of the edge 42 of the cam device 40. The tension in the spring 55 is predetermined to move the point 53 only a short distance for this purpose.

The cam device edge 42 now picks up the point 53 and carries it around to the position 25 in Fig. 4, rocking the lever 51 to the position of that figure. On the outer end of the lever 51 is a roller 94 engaging the under side of the lever 59. The free end of the lever 59 has a depending cam portion 95 terminating in a straight 30 portion 96 normally projecting through a perforation 97 in the panel 13. The movement of the lever 51 causes the roller 94 to ride over the cam portion 95 onto the straight portion 96, moving the lever 59 from the position of Fig. 11 35 to that of Fig. 12. To facilitate this elevating movement of the lever 59, the pin 60 above referred to on which the lever pivots, extends loosely through a perforation in the lever and the lever has a pair of depending ears 98—98 (see Figs. 3, 11, 12 and 13), rounded to rockingly 40 engage the panel 13.

As the lever 59 rises, it raises the roller 93 thereon and with it the finger 84, Figs. 10 and 12, and by the engagement of the intermediate 45 finger 87 with the bracket 89 as described in connection with Fig. 13, raises the tone arm, supporting it by the roller 93 on the inclined lever 59. By the action of gravity, the roller 93 rolls downwardly on the lever 59 rocking the tone arm laterally around the base 12 and at 50 the same time lowering it toward the record.

During these operations, the lever 51 is retained in its oscillated position of Fig. 4 by the point 53 slidingly engaging the rotating cam 55 device edge 42. A spring 99, Figs. 3 and 4, hooked at one end into the arm 54 and at the other end into the eye 56, is put under tension by the rocking of the lever 51 and when the cam device edge 42 leaves the point 53 of the lever, the spring 99 will return the lever 51 60 and associated parts from the position of Fig. 4 to that of Fig. 3, the throw effected by the spring 99 and the inertia of the parts being sufficient to rock the lever 51 to re-engage the dog 57 with the notch 58 against the slight tension thereby 65 created in the spring 55, thus restoring the parts for a second operation.

As the tone arm swings laterally toward the starting point as above referred to, it is first 70 positively stopped and then gradually and gently lowered to position the needle upon the next record, by the mechanism now to be described, the record which has just been played having in the meantime been removed from the pile 75 by mechanism later to be considered.

Projecting upwardly through the panel 13 is a piston rod 100, Figs. 3, 10, and 11, vertically reciprocably guided in a sleeve 101 threaded through the panel 13 and vertically adjustably secured by a nut 102. Adjacent the upper end 5 of the rod 100 a collar 103 is press-fitted onto the rod. A cup-form head 104 having an upwardly outwardly flaring skirt has the cup bottom perforated as at 105 whereby the bottom is telescoped over the upper end of the rod 100 10 and rests upon the collar 103. At the upper end of the rod is a receptacle 106 in which is seated a friction pad 107 of rubber, leather or the like. A compression spring 108 telescoped over the rod and abutting at opposite ends upon the receptacle 106 and upon the cup bottom resiliently constrains the cup-form head 104 to an upright position but permitting it resiliently yieldingly to be tipped on the collar 103 as shown in Figs. 16 and 17.

20

Below the panel 13 the guide sleeve 101 is enlarged to form a cylinder 109 and the rod 100 extends downwardly into the cylinder and on its lower end carries a weight 110 projecting downwardly out of the cylinder; and clamped 25 between the shoulder 111 on the rod and the weight 110 is a cup-form piston 112 of leather or like material adapted to sealingly engage the inner wall of the cylinder 109 when moving downwardly and to create a partial vacuum in 30 the cylinder above the piston but adapted to move upwardly without retardation except by negligible friction. A pad 113 in the upper end of the cylinder 109 cushions and stops upward movement of the piston rod and piston.

35

A lever 114, Figs. 10, 11 and 12 (see also Fig. 4) extends transversely under the panel 13 spaced therefrom, and at one end is supported by a screw 115 projected through a suitable perforation in the lever and threaded into the panel 13 40 and having a lock nut 116 to adjustably position it. A sleeve 117 is provided on the screw 115 between the lever 114 and the panel 13 and loosely reciprocable with lost motion between the lever and the panel; and a spring 118 surrounds 45 the sleeve and abuts at opposite ends on the panel 13 and lever 114. By this means the lever has in general universal movement at the screw-supported end but is prevented from vibrating or chattering by the compression or cushioning 50 spring 118.

55

A hanger rod 119 is secured at one end to the lever 59, extends downwardly therefrom through a perforation 120 in the panel 13, at its lower end is projected through a suitable perforation 55 in the lever 114 and under the latter lever has a pair of nuts 121 threaded on the hanger 119, the nuts supporting the lever 114 on the hanger 60 adjustably. The free end of the lever 114 is bent downwardly and has a lever portion 122 extending under the cylinder 109 and adapted to support the weight 110 and thereby the piston rod 100 and associated parts above described.

65

When the lever 59 above described is in its untripped or lower position, Figs. 3 and 11, the weight 110 and head 104 are in a lower position, the weight 110 lowering the parts to this position by depressing the piston 112, the tendency to create vacuum thereby being relieved by air flowing downwardly through the guide 101 70 through clearance space 123 around the piston rod 100. When the lever 59 is raised in the manner above described to the positions of Figs. 4, 10 and 12, the hanger rod 119 will raise the free end of the lever 114 causing the portion 122 to 75

engage the lower end of the weight 110 and raise the same and therewith the piston rod 100 and head 104 to the position of Figs. 10 and 12, the movement being unretarded due to the cup construction of the piston 112 as well known in the art.

When the tone arm 9 is swung laterally as above described by the roller 93 rolling down the incline of the lever 59, the tone arm will first 10 be stopped upon the elevated head 104 by stop means on the tone arm to be described and then will be supported upon the pad 107 on the piston rod 100 and, the lever 59 being again returned to its depressed position (by the restoring of the 15 lever 51 to its position of Fig. 3 as above described), the weight of the tone arm will move the piston rod 100 downwardly with a retarded motion due to the partial vacuum in the cylinder 109 above described and gently lower the needle 20 upon the record disc.

The stop means for stopping the tone arm against the head 104 will now be described in connection with Figs. 10 and 14 to 17 inclusive. The bracket 89 above described has a finger 123 extending laterally from the tone arm. A screw 124 having an enlarged head 125 is projected downwardly through a slot 126 in the bracket 89, the head 125 overlapping the slot, and below the bracket 89 the screw is telescoped through a 30 sleeve 127 abutting at its upper end upon the under side of the bracket and at its lower end abutting upon a stop element 128. A pair of nuts 129' locked on the lower end of the screw 124 maintains the parts assembled as illustrated 35 in Figs. 10 and 21. The stop element 128 is thus pivotally movable on the screw 124 and comprises a finger 129 and a pair of stop portions 130 and 131 at different distances from the rotational axis of the screw 124. A lug 132 is also 40 formed on the stop element 128.

When the stop element 128 is rocked clockwise, the lug 132 engages a portion of the tone arm 9 as shown in Fig. 14 and then the stop portion 130 is disposed to engage the head 104 to stop the 45 lateral swing of the tone arm in the position for large size or twelve inch records. When the stop element 128 is rocked on the screw 124 to move the lug 132 away from the tone arm 9, the lug 132 will engage an abutment portion 133 50 on the finger 123 to position the stop portion 131 in position to engage the head 104 to position the tone arm for smaller or ten inch records.

To adjustably move both of the stop portions 130 and 131, a screw 134 is projected through a 55 perforation in one of the flanges of the channel-form tone arm 9 as shown in Figs. 10 and 14, and is threaded into the head 125 of the screw 124 and upon turning the screw 134, the head 125 of the screw and therewith the screw itself 60 and thus the pivotal point of the stop element 128, may be adjustably moved forwardly or backwardly in the slot 126 to adjustably position the stops.

When the stop portions are set for the larger 65 records as shown in Fig. 14, and when the stop portion 130 engages the head 104, the finger 123 will be lowered upon the pad 107 as indicated in Fig. 14; and when the stop portion 131 is set in position to stop the arm as shown in Fig. 15, the 70 finger 129 will be lowered upon the head 104 as shown in Fig. 15.

Thus, the lateral swing of the tone arm will be stopped to position the tone arm for either of the two sizes of records as described. When the 75 stop portions engage the head 104, they will rock

the same laterally due to the action of the spring 108 above described, and the head 104 will be tilted as shown in Figs. 16 and 17, where the stop portion 131 is shown engaging the head. The frictional engagement of the pad 107 with the under side of the finger 129 will prevent the spring 108 from restoring the head 104 to its vertical or symmetrical position, the parts remaining as illustrated in Figs. 16 and 17.

The weight of the tone arm now depresses the 10 piston rod 100 to lower the tone arm needle upon the record, and the needle 11 will engage the record as shown in Fig. 17. The weight 110, Fig. 10, will then continue to move the head downwardly until the friction between the pad 107 15 and the finger 129 is relieved. At this time it will be understood that the record 8 is rotating and preferably the needle 11 is on a marginal part of the record radially outwardly from the beginning of the record groove; the needle thus 20 floats unguided on the record. The spring 108 now acts to rock the head 104 to its normal vertical position from the solid line to the broken line positions of Fig. 17, exerting a gentle lateral swinging movement upon the tone arm through 25 the stop portion 131 and gently moving the needle 11 from its solid line to its broken line position, Fig. 17, to move it into the beginning of the record groove. Thus, the needle is not lowered 30 into the groove directly but is gently fed thereinto from the marginal part of the record. As will now be apparent, the needle will be lowered upon the marginal part of the record adjacent the beginning of the groove, whether it be a twelve inch or a ten inch record as predetermined 35 by the stop device above described. And, the distance from the point of engagement of the needle with the record and the beginning groove of the record may be predetermined by adjusting the screw 134 as above described to adjust 40 the stops.

The mechanism for removing the played record from the pile will now be described. As described in connection with Figs. 3 and 4, when the lever 51 was rocked around the pivot 52 to 45 elevate the tone arm and return it to the beginning of the next record, the arm 54 on the lever 51 was likewise given a rocking movement around the pivot 52 from the position of Fig. 3 to that of Fig. 4. A link 135 is pivotally connected at one end to the arm 54 and at the other end is pivotally connected as at 136 to an arm 137 secured to a post 138 extending upwardly from an elongated plate 139, the post having a section of reduced diameter 240 extending downwardly through a perforation in the plate 139 and on through, Fig. 8, a handle element 140 having a laterally extending handle 141, and on through a perforation in the panel 13. A resilient friction washer 142 expandingly engages 60 the under side of the panel 13 and a collar 143 on the extension 240, whereby the post 138, plate 139 and handle element 140 are all resiliently held downwardly upon the top of the panel 13.

The handle element 140 is pivoted as at 144 65 to the panel 13 and may be oscillated thereon, for a purpose to be described. The post extension 240 passes through the handle element 140 at a point laterally or eccentric to the pivot 144.

An upstanding abutment 145 is mounted on 70 the plate 139 adjacent the post 138. At the top of the post 138 is pivoted on a transverse pin 146, a record-lifting arm 147, the arm 147 being vertically oscillatable on the pivot 146 and laterally oscillatable with the post 138. The arm 75

147 has depending therefrom a bracket 148 through which a stud 149 is threaded and locked in position by a nut 150, the end of the stud being disposed to engage the side of the post 5 138 to normally limit downward movement of the arm 147 around the pivot 146.

A finger 151 extends laterally from the arm 147. Forwardly from the pivot 146 the arm 147 has a finger 152 bent downwardly as at 153 and 10 outwardly therefrom bent upwardly as at 154; and pivoted upon the arm at 155 is a second finger 156, and a spring 157 wound around the pivot 155, secured at one end to the arm 147 as at 158 and at its free end 159 engaging a portion 15 15 of the finger 156 rearwardly of the pivot 155 to resiliently hold the finger 156 against the finger 152.

The parts just described are fragmentarily 20 shown in Figs. 6 and 7 in connection with which 20 the operation of these parts will now be described.

Upon oscillatory or rocking movement of the arm 54 as above described, the link 135 will rock the arm 137 and therewith the record-lifting 25 arm 147. The end portion 154 of the arm is thereby brought around into engagement with the upper side of the uppermost record of the pile of records 8—8 and rides thereupon; and 30 sliding thereover, causes the pointed end 160 of the finger 156 to be inserted under the uppermost record. Continued movement of the arm 147 will bring the finger 151 into engagement with the abutment 145 and continued movement will cause the arm 147 to be rocked around the 35 pivot 146 to elevate its outer end, moving the parts from the position shown in Fig. 6 to that of Fig. 7, lifting the engaged side of the record.

The parts are now in the position of Figs. 4 40 and 7 and are held in that position during the continued rotation of the cam edge 42, Fig. 4. The edge of the record diametrically opposite the engaged edge is resting upon the next record immediately thereunder which is rotating, and this supported edge of the record is carried 45 around by the underlying record, the record pivoting on the fingers 156 and 152, and ultimately drops over into the cover 2 as described in connection with Figs. 1 and 2.

After this has been done, the rotating cam edge 42 of Fig. 4 passes from under the pointed end 53 of the lever 51 and the parts return to the position of Fig. 3 and the tone arm is returned to the starting point and lowered upon the next record of the pile.

55 Where the records are twelve inch records, the above described operation may be performed with the parts in the positions of Figs. 3, 4, and 6 to 8. Where the smaller or ten inch size record is to be played, the parts are adjustably 60 moved to the position of Fig. 9 by rotating the handle 141 from the position of Fig. 3 to that of Fig. 9. By this movement, the post extension 140 is oscillated around the pivot 144 from the position of Fig. 3 to that of Fig. 9, giving 65 a longitudinal movement to the plate 139. The movement of the plate is guided by the extension 240 projecting through a circular slot 161 in the panel 13 and by a pin or like projection 162 on the plate projecting downwardly through 70 a radial slot 163 in the panel 13. Thus, by throwing the handle 141 from side to side, the fingers 156 and 152 are moved radially toward and from the pile of discs 8, to position the fingers to pick up the ten inch or the twelve inch records as the case may be. At each 75

adjusted position of the fingers, they are securely retained in their adjusted position by a spring 164 secured at one end to a stud 165, Fig. 8, on the lower side of the panel 13 and hooked at the other end in a cotter pin or other eye 166 secured to the lower end of the extension 140, the spring thus holding the extension 240 securely in one or the other of the ends of the circular slot 161.

By the mechanism and functions described, 10 the pile of records may be played one after the other, and, one after the other, discharged from the pile into the receptacle or cover. When the last record on the turntable alone remains, the record-lifting arm 147 will not pick up the 15 last record because the downward movement of the arm around the pivot 146 will be stopped by the stud 149 on the arm engaging the post 138, whereby the fingers 156 and 153 will swing above the last record without engaging it. The tone 20 arm however will be returned to the starting point as before so that the last record of the pile will be repeatedly played until the mechanism is manually stopped.

To stop the mechanism, the switch 24 may be 25 thrown to the other or "M" position. This will break the motor circuit, Fig. 18, at the contacts 264—264 on the switch 24. This is preferably done while the last record is being played. The motor is thereafter during the playing of the last 30 record supplied with current from the mains 22, Fig. 18, through wires 265—265 to the mechanism operated switch shown generally at 25. This switch comprises a pan-form base 266 preferably formed from sheet metal having 35 flanges 167 adapted to be secured to the under side of the panel 13 and having a depressed portion 168 between the flanges. A pair of resilient switch arms 169 and 170 are secured to a plate 171, for example by rivets not shown, insulated 40 from each other and from the plate 171 by suitable insulation. A screw 172 is projected through the side wall of the pan, Fig. 22, and through a sleeve 173 and threaded into the plate 171, the end of the sleeve engaging the wall of the pan 45 being rounded as at 174. A second screw 175 is projected through the pan wall and through a spring 176 and threaded into the plate 171. The spring 176 and the sleeve 173 position the two switch arms 169 and 170, and by turning the 50 screw 175, the switch arms may be rocked around the rounded end of the sleeve 173 to adjustably position them.

The switch arm 169 has a contact 177 normally engaged with the contact 178 on the switch 55 arm 170. The arm 170 has an extension of fiber or like insulating material 179. The flanges 167 are secured to the under side of the panel 13 in the position to dispose the extension 179 in the path of a pin or like projection 180 on the lever 60 51, Figs. 3 and 18, so that movement of the lever 51 may cause the pin 180 to engage the extension 179 and bend the switch arm 170 to disengage the contacts 177 and 178. For this purpose, a 65 curved slot 181 is provided in the panel 13 for the pin 180 to travel in.

When the switch 24 has opened the contacts 264—264, the current through the motor 5 and the wires 265—265 flows through the switch arms 169 and 170 and through the contacts 177—178. When the last record therefore has been played and the mechanism is tripped as above described and the switch arm 51 is rocked around the pivot 52, the pin 180 will move the switch arm 170 to 75

break the circuit at the contacts 177—178 and open the motor circuit.

The motor circuit will be opened while the arm 51 is being rocked on its pivot 52 and before the point 53 has ridden up on the cam edge 42, Figs. 3 and 4; and thus the torque required to rock the arm 51 and extend the spring 99 and raise the lever 59 and the tone arm therewith, will be load imposed upon the motor through the cam device 40 to absorb the rotational kinetic energy of the motor remaining therein after the current thereto has been broken so very little kinetic energy will be left in the motor after the point 53 of the lever has engaged the circular periphery 5 of the cam edge 42; and the slight braking effect 15 thereof will be sufficient to bring the motor fully to rest with the lever 51 in the position of Fig. 4. The tone arm, however, may return to the starting position.

20 The above description of the operation of the mechanism applies to records having a spiral terminal groove at the center of the record, giving to the tone arm an accelerated impulse of movement at the end of the record groove.

25 Where the other common commercial type of record is used, namely that having an eccentric terminal groove, the operation is similar to that above described after the apparatus is tripped. But to trip the apparatus the following means 30 are utilized.

Referring to Figs. 3 and 11, when the tone arm has been moved toward the center by the playing of the record, the finger 84 moving with the tone arm moves toward the post 68. On the extreme 35 forward end of the finger 84 is a downwardly projecting pawl 182 in the form of a pin with a pointed end. The upper side of the cam arm 63 is provided with a ratchet plate 183 having transverse serrations 184 therein. The pawl 84 idly 40 ratchets over these serrations during movement of the tone arm while playing, being resiliently maintained in engagement therewith by the spring 88 above described which resiliently rocks the three-pronged element 85.

45 When the eccentric terminal groove has been reached by the needle, the tone arm will thereby be given a small lateral oscillatory movement as the record rotates, and this movement is transmitted to the pawl 182 and ratchet plate 184 and moves the cam arm 63 clockwise as viewed in Fig. 3, causing the cam face 65 to slide on the cam follower 67 to rock the lever 59 as above described to trip the mechanism. To facilitate this action, the plate 184 may be given saw-tooth 50 form serrations as shown in Fig. 11 whereby the pawl 182 may move freely thereover toward the post 68 but upon movement in the other direction 55 will move the cam arm 63.

At any time during the playing of a record, 60 whether it be a record on a pile of records or whether it be a single record, the mechanism may be stopped by manually rocking the lever 59 around the pivot 60 by means of a finger piece or lug 185 (see Fig. 3). If the record be one in a 65 pile of records, the record will be discharged from the pile without completing the same and the tone arm will be returned to the starting point of the next record.

If, however, it be desired merely to stop the 70 machine completely, the lever 59 may be tripped by the finger piece 185 and the switch 24 may be thrown to the "M" position. Thereupon, the record in the pile being played will be discharged, the tone arm will be returned to the starting 75 point of the next record and the machine will

stop, the current now being broken on the contacts 177—178 of the switch of Fig. 18.

In cases where there is only one record on the turntable, if the switch 24 is in the "A" position, the record will be repeatedly played, inasmuch as its energizing circuit is maintained at the switch 24 and inasmuch as the discharging device cannot function with a single record, and the mechanism functioning to repeatedly return the tone arm to the start of the record after completing playing thereof and tripping the mechanism.

If, however, it be desired to play the single record only once, the switch 24 may be set in the "M" position whereupon when the record has been completed and the mechanism has tripped, the motor circuit will be opened as described above, the tone arm will be returned to the starting position and the phonograph will stop.

Likewise, while during the playing of a single record the mechanism may be tripped at any point of the playing by operation of the finger piece 185. In such cases, if the switch 24 be in the "A" position, the playing will be interrupted and the tone arm will be returned to the start and the record will be started again; but if the switch 24 be in the "M" position, the tone arm will be returned to the start but the motor will stop and the playing discontinued.

In some cases it has been found that disc records are slightly warped and therefore the top-most record may not engage the record thereunder by which it is rotated, except at a few points, and thus it may slip on the record supporting it causing distortion in the reproduction of the record.

In order to further insure that the top-most record, the one being played, will be positively driven, I prefer to provide means for frictionally engaging the driving shaft with the record. The upper end of the shaft 7, telescoped through the central perforations of the records such as the perforations 188—189, Fig. 19, has a longitudinal slot 189 therein. A wire 190 is projected through the shaft at a point below the end thereof and 45 the end wrapped around the shaft as shown at 191, Fig. 24, and then the wire is bent upwardly, outwardly inclined as shown at 192, and the upper end is again bent downwardly as at 193 disposing it within a bore 195 in the end of the 50 shaft. An upwardly outwardly inclined inwardly radially yieldable spring is thus provided and when the pile of records is placed on the turntable telescoped over the shaft, the spring 192 will engage the periphery of the central hole of 55 the uppermost record as shown in Fig. 19. The friction provided thereby will assist in rotatably driving the top-most record.

The spring 192 is so formed that it will be bent resiliently into the slot by the periphery of the 60 record hole when the top-most record is telescoped thereover, and the upper end of the wire may be provided with an inclined portion 194 to facilitate guiding it into the hole of the record.

As the successive records are played and removed from the pile, the spring portion 192 may 65 resiliently bend farther out of the slot to engage the remaining upper-most record until the second record from the last as shown in 23 is frictionally engaged thereby. The last record may 70 have sufficient frictional drive from the turntable so that the spring 192 may not be needed to drive it, but if preferred, the spring portion 192 may be formed to expand outwardly sufficiently 75 to engage even the last record of the pile.

My invention is not limited to the exact details of construction shown and described. Many modifications and changes may be made within spirit of my invention and the scope of the 5 pended claims.

I claim:

1. In a phonograph mechanism, a record supporting turntable, a laterally swingable tone arm having a record reproducing needle, an electric 10 motor for driving the turntable when energized, a source of current and an energizing circuit for the motor, a switch controlling the circuit, an automatic mechanism for removing the tone arm to a non-reproducing position after reproducing 15 the record and comprising a mechanism element having a normal and an operated position, a trip mechanism actuated by movement of the tone arm at the end of the record reproduction to effect movement of the said mechanism element to 20 its operated position, means operated by the motor for moving the mechanism element from its operated position to actuate the automatic mechanism and for operating the switch to de-energize the motor and thereby stop the turntable, 25 and support means for the tone arm to lower the tone arm from a non-reproducing position to engage the needle with peripheral portions of the record disc, and means to swing the tone arm laterally toward the record to move the record- 30 engaging needle into the record groove.

2. In a phonograph mechanism, a record supporting turntable, a laterally swingable tone arm having a record reproducing needle, an electric motor for driving the turntable when energized, 35 a source of current and an energizing circuit for the motor, a switch controlling the circuit, an automatic mechanism for removing the tone arm to a record starting position, after reproducing the record, and comprising a mechanism element having a normal and an operated position, a trip mechanism actuated by a movement of the tone arm at the end of a record reproduction to effect movement of the said mechanism element to 40 its operated position, means operated by the motor for moving the mechanism element from its operated position to actuate the automatic mechanism and for operating the switch to de-energize the motor to thereby stop the turntable, a manually operable maintaining switch for 45 optionally maintaining energization of the motor to effect continuous driving of the turntable, and support means for the tone arm to lower the tone arm from a non-reproducing position to engage the needle with peripheral portions of the record 50 disc, and means to swing the tone arm laterally toward the record to move the record-engaging needle into the record groove.

3. In a phonograph mechanism, a record supporting turntable, a tone arm having a record reproducing needle, an electric motor for driving the turntable when energized, a source of current and an energizing circuit for the motor, a switch controlling the circuit, an automatic 60 mechanism for elevating and swinging the tone arm to a non-reproducing position after reproducing the record and comprising a mechanism element having a normal and an operated position, a trip mechanism actuated by movement of the tone arm at the end of a record reproduction 65 to effect movement of the said mechanism element to its operated position, means operated by the motor for moving the mechanism element from its operated position to actuate the automatic mechanism and for operating the switch to 70 de-energize the motor and thereby stop the turn- 75

table, a manually operable maintaining switch for optionally maintaining energization of the motor to effect continuous driving of the turntable, the automatic mechanism comprising means to restore the mechanism element to its 5 normal position and re-set the trip mechanism upon return of the arm to non-reproducing position, supporting means for the arm to lower the tone arm from a non-reproducing position to engage the needle with peripheral portions of the 10 disc record, and means to swing the tone arm laterally toward the record to move the record-engaging needle into the record groove.

4. In a phonograph mechanism comprising a vertically swingable tone arm, an element 15 comprising upper, lower and intermediate fingers pivotally connected to the tone arm to oscillate on a generally horizontal axis, a stop associated with the tone arm disposed between the upper and intermediate fingers, a spring urging the element 20 in a direction to engage the upper finger with the stop whereby the tone arm when elevated manually may left the element bodily, and automatic mechanism adapted to engage the lower finger to elevate it to engage the intermediate 25 finger with the stop to thereby elevate the tone arm.

5. In a phonograph mechanism of the class described, a stationary stop element, a tone arm, a supporting element adjustably movable on the 30 arm, a movable stop element pivoted to the supporting element, provided with a plurality of stop portions at different distances from the pivot axis adapted selectively to be pivotally moved into position to engage the stationary stop element 35 to laterally selectively position the tone arm, means for adjusting the stop portions comprising means for adjustably shifting the movable supporting element relative to the tone arm.

6. In a phonograph mechanism of the class described, a stationary stop element, a tone arm, a supporting element adjustably movable on the arm, a movable stop element pivoted to the supporting element, provided with a plurality of stop portions at different distances from the pivot 40 axis adapted selectively to be pivotally moved into position to engage the stationary stop element to laterally selectively position the tone arm, means for adjusting the stop portions comprising a screw anchored against longitudinal 45 movement and threaded into a portion of the supporting element for adjustably shifting the supporting element relative to the tone arm.

7. In an automatic phonograph mechanism comprising a groove-record supporting turntable 5 and a tone arm having a reproducing needle, support means for supporting the tone arm above a record-starting position comprising a stop element and a finger element supported on the arm, a support having a supporting portion engaging 6 the finger element and having a laterally resiliently yieldable stop portion for engaging the stop element, the support being compressible to lower the arm to engage the needle with the marginal portion of the record, the yieldable stop 6 portion exerting lateral thrust on the lowered arm to move the needle laterally into the record groove, and means frictionally engaging the supporting portion and finger element to prevent lateral movement of the arm by the 7 yieldable stop portion while the arm is in the supported position.

8. In an automatic phonograph mechanism of the disc changing type, a turntable adapted to support a pile of records, a main support, a mech- 7

anism including a base movable on the support, and a record-removing mechanism on the base, a handle element pivoted on the main support, a pivot connection between the handle element 5 and the base eccentric of the handle element pivot, a reciprocable guide for the base on the main support whereby when the handle element is oscillatably moved the base and record-removing mechanism may be moved bodily on the main support toward and from the turntable to position the record-removing mechanism for operation upon records of different diameters.

9. In a phonograph mechanism, a turntable, a driving shaft having an end portion extending 15 therefrom adapted to be telescoped by the end thereof through the center holes of a pile of disc records, and means on the shaft portion to frictionally engage the records by their central hole peripheries comprising a resilient element having 20 a portion rigidly secured to the shaft end portion at a point spaced from its disc telescoping end and having a free portion extending toward and beyond the shaft end and yieldable inwardly radially of the shaft end portion and having an 25 inclined portion for guiding the disc record center holes on to the shaft end.

10. In a phonograph mechanism, a turntable, a driving shaft having an end portion adapted to be telescoped by the end thereof through the center holes of a pile of disc records, automatic 30 means for successively removing the successively uppermost record after being played, and means on the shaft to frictionally engage the successive uppermost record by the periphery of its center hole comprising a resilient element having a portion rigidly secured to the shaft end portion at a point spaced from its disc telescoping end and having a free portion extending toward and beyond the shaft end and yieldable 35 inwardly radially of the shaft end portion and having an inclined portion for guiding the disc record center holes on to the shaft end.

11. In a phonograph mechanism comprising a vertically manually swingable tone arm, a tone 40 arm elevating mechanism element, a pivoted element pivotally supported on a generally horizontal pivot axis, stop means on the arm and pivoted element to stop pivotal movement thereof in opposite direction from intermediate positions, 45 means yieldably constraining the pivoted element to pivotally move in one direction and causing it, in an intermediate position, to engage the elevating mechanism element, mechanism means to elevate the elevating element to 50 first move the pivoted element from its intermediate position to its stopped position in one direction and upon further movement to cause it to elevate the tone arm, and, upon manually effected elevational movement of the tone arm, 55 the constraining means maintaining the pivoted element in its stopped position in the other direction whereby, upon further manual elevational movement of the tone arm, the pivot element is engaged by the tone arm stop means effecting continuous pivotal movement of the pivot element in said other direction.

12. In an automatic phonograph mechanism of the type comprising a turntable and a record 60 reproducing tone arm, a turntable drive shaft, an automatic mechanism for returning the tone arm to a non-reproducing position after a record reproduction, comprising a rotary element coaxial with the drive shaft provided with means to actuate the automatic mechanism and having 65 an optimum mechanism actuating speed, a power

supplying motor, power transmission mechanism supplying motor power to the drive shaft at a plurality of different speeds selectively and supplying power to the rotary element at the said optimum speed concurrently with each said selective speed. 5

13. In an automatic phonograph mechanism comprising a disc record and a vertically movable and horizontally swingable record reproducing tone-arm having a reproducing needle, a vertically movable tone-arm support stop means vertically movable with the support and movable laterally thereof by contact with the tone arm, resilient means associated with the stop means opposing lateral movement thereof, means for 15 elevating the support and for elevating the tone arm at the end of a record reproduction and for swinging the tone-arm laterally to cause it to be stopped after contacting the stop means and effecting lateral movement thereof and to be supported in elevated position by the support, the support being then movable downwardly, an air escapement device comprising the sole means for retarding its downward movement, the downward movement of the support depositing the 20 tone arm needle upon the ungrooved margin of the record and permitting the stop means to then force the tone arm laterally toward the record groove, and the support continuing to move to a more depressed position. 30

14. In an automatic phonograph mechanism comprising a disc record turntable, and a vertically movable and horizontally swingable record reproducing tone arm having a reproducing needle, a vertically movable tone arm support, 35 stop means vertically movable with the support and movable laterally thereof by contact with the tone arm, resilient means associated with the stop means and opposing lateral movement thereof, means for elevating the tone arm at the 40 end of a record reproduction and for the swinging the tone arm laterally to cause it to be supported in elevated position by the support, the swinging movement of the tone arm effecting lateral movement of the stop means and being 45 stopped thereby, the support being then movable downwardly, an air escapement device comprising the sole means for retarding its downward movement, and the downward movement of the support continuing beyond the downward movement of the tone arm upon engagement of the tone arm needle with the record ungrooved margin whereby the stop means will be urged laterally in a reverse direction moving the tone arm 50 needle laterally into the record groove. 55

15. In an automatic phonograph mechanism comprising a vertically movable and horizontally swingable record reproducing tone arm, a vertically movable tone arm support, means for elevating the support and for elevating the tone arm 60 at the end of a record reproduction and then for swinging the tone arm laterally to cause it to be supported in an elevated position by the support, the swinging movement of the tone arm being stopped by contact with the support, the support 65 being movable downwardly, and an air escapement device for retarding the downward movement of the support comprising a weighted piston secured to the lower end of the support and movable within a cylinder provided with an air vent. 70

16. In an automatic phonograph mechanism comprising a record supporting turntable and a vertically movable and laterally swingable record reproducing tone arm having a reproducing 75

- needle, a vertically movable tone arm support, means for elevating the support and for elevating the tone arm at the end of a record reproduction, and then for swinging the tone arm laterally
- 5 to cause the tone arm to be supported in an elevated position by the support, the swinging movement of the tone arm being stopped by contact with the support, the support being movable downwardly, an air escapement device retarding
- 10 downward movement of the support, said device comprising a weighted piston secured to the lower end of the support and movable within a cylinder, air vent means for the cylinder, and the downward movement of the support extending beyond
- 15 the downward movement of the tone arm sufficiently to deposit the tone arm needle on the record and to then clear the support from contact with the tone arm.
17. In an automatic record reproducing mechanism, a tone-arm-lowering device comprising a reciprocably movable member for receiving and lowering the tone-arm onto a record, means for restricting the lowering speed of said member, said member being constructed and arranged to
- 20 move to a position free of engagement with the tone-arm when the latter engages the record, means for urging the tone-arm inward radially of the record when the tone-arm is free of said member, means for raising said tone-arm and
- 25 moving it radially outward upon completion of the reproduction of the record, means for raising said member to a position to receive said tone-arm, and a linkage between said last two means to effect simultaneous operation thereof.
- 30 18. In an automatic phonograph mechanism, a main frame, a turntable carried by said frame, a tone-arm swingable over said turntable, a tone-arm-lowering post adjacent to said turntable, a lifting mechanism for lifting the tone-arm-lowering post to a position to receive the tone-arm after the completion of the playing of the record and for subsequently withdrawing support from the tone-arm-lowering post, a tone-arm lifting mechanism for lifting the tone-arm from
- 35 the record after the playing thereof and swinging it into engagement with the tone-arm lowering post, and a dash-pot for restricting the lowering speed of the tone-arm-lowering post as it lowers the tone-arm onto a record after the withdrawal of the support for the post.
- 40 19. In an automatic phonograph mechanism, a main frame, a turntable carried by said frame, a tone-arm swingable laterally over the turntable, a stop member on said tone-arm, a tone-arm elevating mechanism for raising the tone-arm from a record after the completion of the playing thereof and for swinging it to an elevated record-starting position, a tone-arm-lowering device for receiving the tone-arm in the elevated record
- 45 starting position and for lowering it onto a record, comprising a tone-arm-lowering post normally out of engagement with the tone-arm; a dash-pot mechanism for restricting the lowering speed of the post, and a lifting mechanism interconnected with the tone-arm elevating mechanism for lifting the post to position it to receive the tone-arm with the stop on the tone-arm engaging the head of the post, and for subsequently withdrawing support from the lowering post to
- 50 permit it to lower the tone-arm onto the record.
- 55 20. In an automatic phonograph mechanism, a main frame, a turntable carried by said frame, a tone-arm swingable laterally over the turntable,
- 5 to a stop member on said tone-arm, a tone-arm elevating mechanism for raising the tone-arm from a record after the completion of the playing thereof and for swinging it to an elevated record-starting position, a tone-arm-lowering device for receiving the tone-arm in the elevated record starting position and for lowering it onto a record, comprising a tone-arm-lowering post normally out of engagement with the tone-arm, an air escapement device for restricting the lowering speed of the post having a weighted piston secured to the lower end of the post and movable within a cylinder provided with an air vent, and a lifting mechanism interconnected with the tone-arm-elevating mechanism for lifting the post to position it to receive the tone-arm with the stop on the tone-arm engaging the head of the post, and for subsequently withdrawing support from the lowering post to permit it to lower the tone-arm onto the record.
- 10 21. In an automatic phonograph mechanism, a main frame, a turntable carried by said frame, a tone-arm swingable laterally over the turntable, a stop member on said tone-arm, a tone-arm elevating mechanism for raising the tone-arm from a record after the completion of the playing thereof and for swinging it to an elevated record-starting position, a tone-arm-lowering device for receiving the tone-arm in the elevated record-starting position and for lowering it onto a record, comprising a tone-arm-lowering post normally out of engagement with the tone-arm, an air escapement device for restricting the lowering speed of the post having a weighted piston secured to the lower end of the post and movable within a cylinder provided with an air vent, and a lifting mechanism interconnected with the tone-arm-elevating mechanism for lifting the post to position it to receive the tone-arm with the stop on the tone-arm engaging the head of the post, and for subsequently withdrawing support from the lowering post to permit it to lower the tone-arm onto the record.
- 15 22. In an automatic record-reproducing mechanism a tone-arm-lowering device comprising a reciprocably movable post for receiving a tone-arm, means for moving said post downward to a position free of said tone-arm, to thus place the tone-arm on a record, a dash-pot for restricting the lowering speed of said post, and a laterally displaceable resiliently mounted member on said post for urging the tone-arm inward radially of the record when the tone-arm is free of said post.
- 20 23. In an automatic record-reproducing mechanism, a tone-arm-lowering device, comprising a reciprocable member having an end adapted to receive and support the tone-arm, a flared member loosely carried by said reciprocable member and adapted for lateral engagement by said tone-arm, and spring means arranged cooperatively with the flared member so as to resist displacement thereof and to urge said flared member to normal position, whereby said displaceable member when laterally displaced by the tone-arm exerts pressure thereon to urge the tone-arm into initial reproducing position when the tone-arm engages a record to be reproduced.

PAUL U. LANNERD.
